United States Patent Office.

JAMES E. GILLESPIE, OF BOSTON, MASSACHUSETTS.

Letters Patent No. 64,660, dated May 14, 1867.

IMPROVED ROD-CUTTER.

The Schedule referred to in these Letters Patent and making part of the same.

Be it known that I, JAMES E. GILLESPIE, of Boston, in the county of Suffolk, and State of Massachusetts, have invented a new and useful Machine for Cutting Rods of Iron or other substances; and I do hereby declare that the following is a full, clear, and exact description of the construction and operation of the same, reference being had to the annexed drawings, making a part of this specification, in which—

Figure 1 is a transverse section.

Figure 2 is a longitudinal section through the lower line of holes; and

Figure 3 is a longitudinal elevation.

Similar letters of reference are used to designate the same parts in all the figures.

In fig. 1, A A C is the shell of iron, which is shown also in figs. 2 and 3. B B are steel dies, with a series of perforations or holes, 3, 4, 5, 6, 7, &c. C C, figs. 1 and 3, are lugs or ears for fastening the shell together; and J J, fig. 3, are feet, by means of which the machine is fastened to the bench. The perforated plate or die B D is made longer than the other at one end, and it is fitted to slide freely horizontally in its seat or socket, and has a spring at one end, K, figs. 2 and 3, to keep it back in its true position, which is with its end D bearing against the cams 2 2 2, fig. 3. This cam can be made with the handle H projecting directly from it, and thus make but a half revolution, or it can continue around as shown by dotted lines 1 1 1. When the cam is so formed as to make a whole revolution the lever or handle H can be fastened to the shaft G, and act as a crank to force the cam against the die D. Below the dies, near the cam, is the gauge E F, the lever N, which projects from the sleeve or thimble of the gauge, and bears against the cam. The rod E E passes through the sleeve, and is held in position by the set-screw, and can be set to any length.

The operation of my improved rod-cutter is as follows, viz: A rod is passed into and through one of the holes in the dies, which are always opposite each other. The gauge having previously been set to the right length the rod will stop when it comes to it, and is in position to be cut off, which is done by raising the lever or handle, thereby turning the cam and forcing the die forward, while its mate remains still in its seat, by which means the rod is cut off. At the same time the cam depresses the lever N of the gauge and turns the shaft E, thereby raising the arm of the gauge F out of the way so as to let the cut-off end of the rod be removed. The gauge again returns to its position, when the cam comes to its normal position.

I am aware that movable gauges have been used before, but not arranged as conveniently as mine; I do not, therefore, claim the gauge nor the dies by themselves; but what I claim as my invention, and desire to secure by Letters Patent, is—

A rod-cutter constructed and operated substantially as specified.

JAMES E. GILLESPIE.
